Dennis Visscher, Muskegon, Mich., assignor to Beatrice Foods Co., Chicago, Ill.

Filed Oct. 2, 1972, Ser. No. 294,377

Term of patent 14 years

Int. Cl. D12—02

U.S. Cl. D12—29

FIG. 1 is a perspective view of a cart showing my new design;

FIG. 2 is a top plan view thereof;

FIG. 3 is a left end elevational view thereof;

FIG. 4 is a side elevational view thereof; and

FIG. 5 is a right end elevational view thereof.

The broken lines on the drawing are shown for illustrative purposes only.

I claim:

The ornamental design for a cart, as shown and described.
